F. G. WHITTINGTON,
LAMP SUPPORTING DEVICE,
APPLICATION FILED JUNE 23, 1920.

1,374,268.

Patented Apr. 12, 1921.

UNITED STATES PATENT OFFICE.

FREDERIK G. WHITTINGTON, OF CHICAGO, ILLINOIS, ASSIGNOR TO STEWART-WARNER SPEEDOMETER CORP., OF CHICAGO, ILLINOIS, A CORPORATION OF VIRGINIA.

LAMP-SUPPORTING DEVICE.

1,374,268.

Specification of Letters Patent.

Patented Apr. 12, 1921.

Original application filed December 5, 1919, Serial No. 342,586. Divided and this application filed June 23, 1920. Serial No. 391,128.

To all whom it may concern:

Be it known that I, FREDERIK G. WHITTINGTON, a citizen of the United States, residing in the city of Chicago, in the county of Cook and the State of Illinois, have invented certain new and useful Improvements in Lamp-Supporting Devices, of which the following is a specification, reference being had to the accompanying drawings, forming a part thereof.

This application is a division of my pending application, No. 342,586, filed December 5, 1919. The invention of this present divisional application is an improvement in lamp supporting devices. It consists in the elements and features of construction shown and described, as indicated in the claims.

In the drawings:

Figure 1 is a plan view of a lamp or searchlight having supporting devices embodying this invention.

Fig. 2 is a detail section at the line 2—2 on Fig. 1.

Fig. 3 is a section at the line 3—3 on Fig. 2.

Fig. 4 is an elevation looking in the direction of the arrow, 4, on Fig. 1.

The vehicle lamp illustrated in the drawings, comprising the focusing reflector, 1, cover glass, 3, secured by the ring, 4, at the front of said reflector, and inclosing a lamp bulb, has a tubular stem, 5, in which the lamp socket tube, 6, is mounted for adjustment axially of said stem. The detailed construction for holding and adjusting the lamp bulb, connecting the current wires and operating for opening and closing the circuit, are set out in my application, Serial No. 342,586, of which this application is a division, and these features are not to be claimed in the present application.

The stem, 5, has a transversely extending stem, 8, secured to said stem, 5, in a manner which is fully described in my said application, No. 342,586, and not to be claimed herein. Said stem, 5, constitutes the means by which the lamp is adjustably mounted in a holder, which, with the means of such mounting and of mounting said holder, will now be described.

The usual support upon a vehicle for a lamp of this character, is a vertical member, such as a frame of a windshield of an

automobile; and for attaching the lamp to such a part there are provided clamping jaws, 11, adapted to be drawn together by clamping bolt, 12. The jaws, 11, extend from a triangularly bent member whose sloping side portions, 13, are connected by a transverse portion, 14, from whose edges there are bent circular ears, 15, which extend in planes perpendicular to the plane of the part, 14, and cover the edges of the sides, 13, of the triangular outline mentioned, forming a box-like structure, so that similar ears, 16, formed as hereinafter described, may be clamped against the ears, 15, by a clamping bolt and pivot member, 17, which is provided with a spring washer, 18, and a friction washer, 19, permitting the parts to be clamped with considerable firmness so as to be frictionally held quite firmly in place while yet allowing of adjustment about the pivot, 17, without releasing the nut of the clamping bolt.

The ears, 16, are formed as integral extensions of a cylindrical clamping member, 20, embracing the tubular stem, 8, above mentioned, and provided with perforated lugs, 21, through which the stem of the clamp screw, 22, extends for securing the stem, 8, frictionally against rotation in the part, 20. And at this point also, it may be understood, that the clamping is designed to be only firm enough to maintain any given adjustment, while permitting readjustment of the clamp about the axis of the stem 8, without requiring release of the clamping screw, 22. To permit such rotation of the stem, 8, within the member, 20, and at the same time prevent it from being withdrawn longitudinally therefrom, a groove, 23, is formed in the stem, 8, and locking member, 24, is clamped in position on the screw, 22, said locking member having a projecting nose, 25, engaging the groove, 23.

As indicated in Fig. 2, the part, 24, is secured between one of the lugs, 21, and the head of the clamp screw, 22; and, as shown in Fig. 1, the nose, 25, projects through a slot, 20^a, cut in the member, 20, adjacent to the lug, 21. The slot, 20^a, is of such length as to limit the rotation of the member, 24, about the clamping screw, 22, in one direction, but to permit it to rotate out of engagement with the groove, 23,

when the clamp screw, 22, is released, and the tubular stem, 8, is withdrawn from the clamp, 20, as indicated in Fig. 3.

When the lamp is thus disengaged from its support, it may be employed for various purposes, as in removing an injured tire or making other repairs about the vehicle, sufficient extra length of lead wires, 29 and 30, being provided for this purpose.

10. In replacing the stem, 8, in the clamping socket, 20, the locking member, 24, may be turned with its nose projecting into the cylindrical space, and before the clamp screw, 22, is tightened, the parts will yield sufficiently to permit the extreme end of the tubular stem, 8, to pass the nose, 25, the latter snapping into the groove, 23, as that portion of the stem arrives in registration with it. Then by tightening the clamp screw, 22, 20 the parts will be again assembled, and the light beam projected by the focusing reflector, 1, can be directed as desired by swinging the lamp bodily, either about the axis of the bolt, 17, or else about the axis of 25 the stem, 8, these two axes being perpendicular to each other; and there is thus provided a universal mounting for the lamp body.

I claim:

30. 1. In combination with a vehicle lamp provided with a supporting stem, a holder embracing said stem and provided with a pair of perforated ears spaced apart, a clamp comprising a pair of jaws formed in-

tegrally of the respective ends of a sheet 35 metal member folded at two places near the middle of its length, to leave a transverse middle portion connecting the two jaw-carrying parts, perforated ears bent from the edges from said middle portion on to 40 the adjacent edges of the jaw-carrying part to provide bearing area for the ears of the stem holder which are lapped over them and a pivot bolt extending through the ears of both parts holding them in frictional engagement.

2. In combination with a lamp body provided with circumferentially grooved cylindrical stem, a holder embracing said stem and including lugs spaced apart and connected by clamp screw having head or shoulder, and a locking member rotatively adjustable upon said clamp screw adjacent to its head or shoulder, and having a nose formed to project into the groove of said 55 stem for locking the stem in the holder.

3. In the combination defined in claim 2, foregoing, a clearance slot through which said nose of the locking member projects for engaging the groove, said slot being dimensioned to permit rotation of said nose out of the groove when the clamp screw is released.

In testimony whereof, I have hereunto set my hand at Chicago, Illinois, this 16 day of 60 June, 1920.

FREDERIK G. WHITTINGTON.
